UNITED STATES PATENT OFFICE.

FREDERICK A. BOLLINGER, OF AKRON, OHIO.

TRAIN-CONTROLLING APPARATUS.

1,257,794.

Specification of Letters Patent. Patented Feb. 26, 1918.

Application filed August 26, 1915. Serial No. 47,442.

To all whom it may concern:

Be it known that I, FREDERICK A. BOLLINGER, a citizen of the United States, residing at Akron, in the county of Summit 5 and State of Ohio, have invented new and useful Improvements in Train-Controlling Apparatus, of which the following is a specification.

This invention relates to improvements in 10 train controlling apparatus whereby the propelling power of a motor car will be cut off and the brakes applied in the event of the train running into a danger zone, and whereby a train will be protected both from 15 rear-end and head-on collisions.

In carrying out my invention, I employ two sets of track obstacles and the obstacles in each set are arranged along the trackway and appropriately spaced apart and 20 disposed adjacent to the obstacles, respectively, in the other set. Each track obstacle embodies an actuator capable of movement to active and inactive positions, and an electroresponsive device for moving the 25 actuator to active position and an analogous device for moving the actuator to inactive position. Associated with each track obstacle is a controlling switch and the controlling switch of each obstacle is connected in 30 circuit with the first-mentioned electroresponsive device of the obstacle in the same set at one side of the particular obstacle and with the second-mentioned electroresponsive device of the obstacle in the same set at the 35 same side of the particular obstacle, and also with the second-mentioned electroresponsive device of the adjacent obstacle in the other set and with the first mentioned electroresponsive device of the obstacle be- 40 yond said adjacent obstacle in the other set so that the first-mentioned controlled obstacles will be rendered active and the last-mentioned controlled obstacles inactive in the operation of the controlling switch as- 45 sociated with the particular controlling obstacle. Each obstacle is equipped with a signal operable in the operation of the actuator under the first-mentioned electroresponsive device to indicate the active condi- 50 tion of the obstacle, while a second signal is provided for each obstacle and operable in the operation of the actuator under the second-named electroresponsive device to indicate the inactive condition of the obsta- 55 cle.

The actuator of each obstacle may control

a car carried stopping mechanism, while the controlling switches of the obstacles are under the control of operating devices carried by each train and as soon as the actuator of a particular obstacle is in inactive position the controlling switch associated with such obstacle is in condition to be influenced by the operating device on a passing train to render the controlled obstacles active, 60 while when an actuator of a particular obstacle is in active position, the controlling switch associated with such obstacle is out of position to be influenced by the operating device on a passing train, thereby enabling 65 the engineers of trains to reverse the direction of travel of their trains on the trackway without disturbing the condition of the obstacles that are caused to operate proceeding in the normal direction of traffic, and 70 preventing such reversed trains from running into a train proceeding in the normal direction of traffic.

My invention consists in the construction, combination and arrangement of parts hereinafter set forth in and falling within the 80 scope of the claims.

In the accompanying drawings:

Figure 1 is a fragmentary transverse sectional view through a motor car showing 85 my invention installed, the track obstacles and car carried mechanism being shown in elevation.

Fig. 2 is a longitudinal sectional view through one of the track obstacles. 90

Fig. 3 is a similar view on the line 4—4 of Fig. 2.

Fig. 4 is a like view on the line 5—5 of Fig. 2.

Fig. 5 is a fragmentary horizontal longitudinal sectional view through one of the obstacles. 95

Fig. 6 is a vertical sectional view through the operating device carried by the motor car.

Fig. 7 is a diagrammatic view showing 100 the circuit connections between the track obstacles.

Referring now to the drawings in detail, 1 and 2 designate sets of track obstacles. 105 The obstacles in the set 1 are arranged along the trackway and spaced apart appropriate distances, while the obstacles in the set 2 are similarly spaced and arranged between or alternated with the obstacles in the set 1. 110 In the present instance, each obstacle comprises, an elongated casing 3 substantially

rectangular in cross section and having the lower wall thereof formed, approximately centrally, with an elongated longitudinally extending slot 4. Secured to the bottom 5 wall of the casing 3 and projecting upwardly therefrom are standards 5, 5 suitably spaced apart and each equipped with bearing rollers 6, 6 spaced apart vertically and alining with the respective rollers on the other standards. Passed through the spaces between the rollers 6, 6 on the standards 5 and capable of longitudinal sliding movement upon such rollers is a shaft 7 having one end 10 equipped with a core 8 under the control of a solenoid 9 and the opposite end equipped with a core 10 under the control of a solenoid 11. Fixed to the shaft 7 between the standards 5, 5 and depending from the shaft and extending through the slot 4 are supporting arms 12 and mounted in the lower 15 ends of the supporting arms 12 below the casing 3 is a shaft 13 upon which is rotatably mounted a roller 14 having the periphery thereof formed with a groove 15. Surrounding the shaft 13 at opposite sides of the roller 14 are coiled expansion springs 16 having the inner ends bearing against the respective sides of the roller and the outer 20 extremities abutting the lower ends of the arms, the springs acting to hold the roller 14 upon the central portion of the shaft 13 and to restore the roller to such position in the event of the roller being moved longitudinally along the shaft. The arms 12, 25 shaft 13, roller 14 and springs 16 constitute an actuator and when the solenoid 9 is energized, the shaft 7 is moved longitudinally in one direction to shift the actuator to inactive position, while when the solenoid 11 30 is energized the shaft 7 is moved longitudinally in the opposite direction to shift the actuator to active position. Although I have illustrated and described the electroresponsive devices for actuating the shaft 7 as 35 composed of solenoids and cores, it is conceivable that other devices may be employed for shifting the shaft and actuator. Secured to the bottom wall of the casing 3 in juxtaposition to the inner extremities of the 40 solenoids 9 and 11 respectively are circuit breakers 17 and 18, each comprising, in this instance, a base plate 19 formed with an upwardly projecting arm 20 at one end thereof carrying a contact 21, and formed 45 with upwardly projecting ears 22 adjacent to the opposite end thereof. Pivoted between the ears 22 is a movable contact finger 23 normally held in engagement with the contact 21 by means of a spring 24. Each 50 circuit breaker is connected in circuit with the winding of the adjacent solenoid and secured to the shaft 7 in proximity to the cores 8 and 10 are collars equipped with 55 downwardly projecting arms 26. Secured to 60 the upper end of each arm 26 is a contact 65

27, while fastened to the top wall of the casing 3 are brackets 28 upon which is disposed adjacent to the respective solenoids 9 and 11 and secured to each bracket 28 and depending therefrom a contact 29 adapted to be engaged by the adjacent contact 27. In the present instance, each contact 29 is capable of slight vertical movement and interposed between each bracket 28 and the contact 29 thereon are coiled expansion springs 30, acting to cushion the upward movement of the contact 29 when engaged by the contact 27 and serving to insure good electrical contact between the members 29 and 27. As the shaft 7 approaches its limit of movement under the action of the solenoid 9 and core 8, the depending arm 26 engages the movable contact finger 23 and swings such finger against the action of the spring 24 out of engagement with the contact 21, thereby breaking the circuit of the solenoid 9. At the same time, the contact 27 engages the contact 29. Similarly, when the shaft 7 approaches the limit of its movement under the action of the solenoid 11, the adjacent arm 26 engages the finger 23 of the adjacent circuit closer and swings such finger against the action of the spring 24 out of engagement with the contact 21, thereby breaking the circuit of the solenoid 11. Simultaneously with this operation of the circuit breaker, the contact 27 on the arm 26 carried by the adjacent collar rides into engagement with the companion contact 29. In the present instance, the contacts 27 and 29 in proximity to the solenoid 9 are connected with the respective terminals of a signal lamp 31 indicative of safety, while the similar contacts adjacent to the solenoid 11 are connected with the respective terminals of a signal lamp 32 indicative of danger. Fastened to the shaft 7 and movable bodily with the shaft is a pawl and ratchet controlling switch 33 equipped with an operating arm 34, while slidably mounted within an opening in the bottom wall of the casing and a bearing 35 alining with such opening is a vertical rod 36 having the upper end thereof equipped with a head 37 adapted to engage the arm 34 to swing the latter to actuate the switch 33 to circuit closing position. Secured to the lower end of the rod 36 and depending therefrom is a segmental plate 37'. Surrounding the lower portion of the rod 36 and suitably fixed thereto is a cross bar 38 and secured to the ends of the cross bar 38 and depending therefrom at opposite sides of the plate 37' are arms 39, 39 and secured to the lower extremities of the arms 39, 39 respectively, are curved guide plates 40 having the extremities thereof diverging outwardly from each other to form entrance mouths for the guide way between the plates. Surrounding the rod 36 between the bottom wall of the casing and the cross

bar 38 is an expansion spring 41 acting to hold the rod 36 normally in lowered position so that the head 37 will be out of engagement with the arm 34 of the switch 33.

5 The switch 33 of each obstacle is connected in circuit with the solenoid 11 of the obstacle in the same set at one side of the particular obstacle by means of conductor 11', and with solenoid 9 of the second obstacle of the 10 same set on the same side by means of a conductor 43, and with the solenoid 11 of the obstacle in the other set at the opposite side of the particular obstacle by means of conductors 11''. The switch 33 of each obstacle 15 is also connected with the electroresponsive device 9 of the adjacent obstacle in the other set by means of conductors 44, as clearly illustrated in Fig. 13 of the drawings.

As long as the shaft 7 of the track obstacle 20 is in a position to hold the actuator inactive, the arm 34 of the switch 33 is disposed in the path of movement of the head 37 on the upper end of the rod 36 so that in the upward movement of the rod 36 against the action 25 of the spring 41, the head 37 will engage the arm 34 and actuate the switch 33 to circuit closing position, thereby energizing the solenoids 11 of the obstacles in advance of and behind the particular obstacle and energizing 30 the restoring solenoid 9 of the obstacle immediately adjacent to the particular controlling obstacle. Thus, the actuators of the obstacles behind and in advance of the particular controlling obstacle will be shifted 35 to active position, and the actuator of the obstacle immediately adjacent to the particular controlling obstacle shifted to inactive position. When the shafts of the respective obstacles reach their limit of movement 40 under the action of the particular energized solenoids, the circuits of such solenoids are automatically broken, incident to the arms 26 actuating the circuit breakers connected in circuit with such solenoids and 45 the corresponding lamps are energized, thereby indicating the condition of the obstacle so that an engineer approaching the obstacle and seeing the signal lamp may control his train accordingly.

50 Slidably mounted within the top wall of the motor car is an operating device comprising a vertical shank 100 having the upper end formed with a yoke 101 carrying a horizontal shaft 102 upon which is rotatably 55 mounted a peripherally grooved roller 103 adapted to ride into engagement with the segmental plates 37 of the track obstacles.

The roller 103 is held upon the central portion of the shaft 102 by means of coiled 60 expansion springs 104. The operating device on the motor car is normally held in elevated position by means of a pin 105 passed through alining openings in one of the bearings of the shank and when it is 65 desired to lower the operating device so that

the roller 103 may pass the segmental plates 37 without engaging the latter, the pin 105 is withdrawn from the alining openings and the shank pulled downwardly.

From the foregoing description taken in connection with the accompanying drawings, the construction, and mode of operation of my improved train controlling apparatus will be readily apparent. It will be seen that when a train passes a track obstacle and the operating device thereon is in elevated position the roller 103 will engage the segmental plate 37 of the adjacent track obstacle with the effect to move the rod 36 upwardly and actuate the switch. 75 80

The adjacent track obstacles of the respective sets are so arranged that the plates 37 are adapted to be engaged by the operating devices of trains moving in reverse directions respectively, while the actuators are 85 all disposed at the center of the trackway when active. Switch 33 is adapted to be momentarily closed and automatically reopened upon contact of a train carried device such as roller 103 with plate 37' and as 90 shown in Fig. 13, is connected in circuit with solenoid 11 of an adjacent obstacle of the same series, and with solenoid 9 of the obstacle of the same series beyond said adjacent obstacle, and with solenoid 9 of an adjacent obstacle of the other series, and with solenoid 11 of the obstacle of the other series 95 beyond said adjacent obstacle of such series.

Solenoids 11 being adapted to set the signals and obstacles to danger, and solenoids 100 9 being adapted to set the signals and obstacles to safety, it thus follows that upon a train passing a given obstacle of the series corresponding to the direction of travel, the obstacle of the same series immediately in 105 the rear will be set to danger, thus affording protection from a following train. At the same time the second obstacle to the rear will be set to safety. In the other series, the second obstacle from the given obstacle 110 in the direction of travel will be set to danger, affording protection from a train coming from the opposite direction, and the adjacent obstacle of the other series will be set to safety. 115

While I have herein shown and described certain preferred forms of my invention by way of illustration, I wish it to be understood that I do not limit or confine myself to the precise details of construction herein 120 described and delineated, as modification and variation may be made within the scope of the claims and without departing from the spirit of the invention.

I claim:

1. In train controlling apparatus, a set of obstacles spaced along the trackway, a controlling device for other obstacles of said set associated with each obstacle, and means governed by said controlling devices where- 125 130 135

by upon the actuation of a particular controlling device an obstacle of said set will be moved to an operative position, and the associated controlling device will be moved to an inoperative position.

2. In train controlling apparatus, a set of track obstacles spaced along the trackway, a second set of track obstacles spaced along the trackway, and a controlling device associated with each obstacle of said first and second sets; operating means for each obstacle, and circuit connections between said controlling devices and said operating means whereby upon actuation of a particular controlling device of one set the adjacent obstacle of the other set will assume the safe position and the obstacle of the other set on one side of the particular controlling device will assume the danger position; and the obstacle of the first-mentioned set on the other side of the particular controlling device will assume the danger position and the second obstacle of the first-mentioned set on the last-mentioned side of the particular controlling device will assume the safe position.

3. In train controlling apparatus, track obstacles arranged along the trackway and spaced apart, each comprising a horizontal shaft capable of longitudinal sliding movement, an actuator on said shaft capable of movement to active and inactive positions under the action of the shaft, an electroresponsive device for moving said shaft in one direction to render said actuator active, an electroresponsive device for moving said shaft in the opposite direction to render said actuator inactive, and a switch associated with each obstacle and controlling the first-mentioned electroresponsive devices of certain other obstacles and the last-mentioned electroresponsive device of another obstacle.

4. In train controlling apparatus, track obstacles arranged along the trackway and spaced apart, each comprising a horizontal shaft capable of longitudinal sliding movement, an actuator on said shaft capable of movement to active and inactive positions under the action of the shaft, an electroresponsive device for moving said shaft in one direction to render said actuator active, an electroresponsive device for moving said shaft in the opposite direction to render said actuator inactive, a switch associated with each obstacle and controlling the first-mentioned electroresponsive devices of cer-

tain other obstacles and the last-mentioned electroresponsive device of another obstacle, and mounted upon said shaft and movable bodily with the shaft, and means for actuating said switch when the associated actuator is in inactive position whereby the controlled obstacles may be operated.

5. In train controlling apparatus, track obstacles arranged along the trackway and spaced apart, each comprising a horizontal shaft capable of longitudinal sliding movement, an actuator on said shaft capable of movement to active and inactive positions under the action of the shaft, an electroresponsive device for moving said shaft in one direction to render said actuator active, an electroresponsive device for moving said shaft in the opposite direction to render said actuator inactive, a switch associated with each obstacle and controlling the first-mentioned electroresponsive devices of certain other obstacles and the last-mentioned electroresponsive device of another obstacle, and means for breaking the circuit of each electroresponsive device upon the shaft reaching its limit of movement under the action of such device.

6. In train controlling apparatus, track obstacles arranged along the trackway and spaced apart, each comprising a horizontal shaft capable of longitudinal sliding movement, an actuator on said shaft capable of movement to active and inactive positions under the action of the shaft, an electroresponsive device for moving said shaft in one direction to render said actuator active, an electroresponsive device for moving said shaft in the opposite direction to render said actuator inactive, a switch associated with each obstacle and controlling the first-mentioned electroresponsive devices of certain other obstacles and the last-mentioned electroresponsive device of another obstacle, means for breaking the circuit of each electroresponsive device upon the shaft reaching its limit of movement under the action of such device, and means on said shaft for actuating the first-mentioned means.

In testimony whereof I affix my signature in presence of two witnesses.

FREDERICK A. BOLLINGER.
